AIR SCRABBLER SYSTEM FOR THE AIR DEPOSITION OF FIBERS

Bror E. Anderson, Park Ridge, Ill., assignor to A. B. Dick Company, Niles, Ill., a corporation of Illinois

Application January 13, 1955, Serial No. 481,632

14 Claims. (Cl. 19—148)

This invention relates to the air deposition of dry fibers in the manufacture of fibrous structures and it relates more particularly to an improvement in the method and apparatus for the manufacture of fibrous structures such as described and claimed in the copending application of Clark et al., Ser. No. 313,316, and entitled "Air Scrabbler System for Fiber Deposition in the Manufacture of Fibrous Structures." In the above-entitled copending application description is made of a fiber depositing system which embodies the principles of a shower-head to cause uniform volumes of fiber and air to pass through the openings of a foraminous separating wall to a collecting wall where the fibers separate out on the surfaces thereof to form a fibrous structure. Briefly described, the fiber depositing head comprises a cylindrical housing having a fiber inlet opening in one wall portion and a foraminous separating wall in another portion of the cylindrical housing. The shower-head principle is created by introducing one or more high velocity streams of air tangentially into the housing whereby the fibers become entrained therein and are carried with the air circumferentially about the housing to form a transient layer of air and fibers moving under positive pressure across the face of the separating wall. The constant movement of the fibers and air across the face of the separating wall functions effectively to keep the openings substantially free of entrapped fibers so that fibers and air under positive pressure are able to pass through the openings in substantial constant and uniform volumes to deposit a uniform distribution and concentration of fibers on the surface of the collecting wall.

It is an object of this invention to provide further improvements in apparatus of the type described for the air deposition of dry fibers in the manufacture of fibrous structures.

Another object is to produce apparatus of the type described adapted to impart greater movement to the air and fibers moving about the cylindrical housing and also to provide means for more uniform distribution and separation of the fibers entrained within the air stream.

It is a related object to provide an improvement in apparatus of the type described adapted to produce improved fibrous structures wherein separated fibers are deposited in more uniform distribution and to provide a method for producing same.

These and other objects and advantages of this invention will hereinafter appear, and for purposes of illustration, but not of limitation, embodiments are shown in the accompanying drawing in which—

Figure 1 is a schematic sectional elevational view of a fiber depositing head embodying features of this invention;

Figure 2 is a schematic sectional elevational view similar to that of Figure 1 embodying a modification in the assembly for securing more desirable fiber distribution;

Figure 3 is a sectional elevational view corresponding

2

to that of Figures 1 and 2 embodying a further modification in a fiber depositing head; and

Figure 4 is a sectional elevational view taken substantially along the line 4—4 of Figure 3.

As shown in Figure 1 of the drawing, a fiber depositing head embodying features of this invention comprises an outer cylindrical housing 10 having a feed chute 11 in communication with a feed opening 12 in the upper wall portion for introducing separated fibers into the cylindrical housing. The feed opening 12 may extend over only a portion of the housing but it is preferred to have the feed opening extend substantially across the housing so as to be able to introduce fibers in substantially uniform distribution across the entire width of the housing.

The underside of the housing is provided with a separating wall portion 13 preferably in the form of a separated plate secured to the underside of the housing or else formed as an integral part thereof. The foramen in the separating wall may comprise elongate slots extending transversely across the housing in circumferentially spaced apart relation or they may be in the form of separate openings such as exist in screen members, or in plates of the type described in the copending application of James d'A. Clark, Ser. No. 61,674, filed November 23, 1948.

One or more air nozzles 14 are positioned to extend within the housing to direct one or more high velocity streams of air in a tangential direction to impart circulating movement of the air about the housing. These air nozzles may be positioned in separate inlets arranged laterally across the housing to introduce a plurality of tangential streams of air directed at corresponding or at varying angles but preferably in a direction less than radial and in a direction other than to direct the air stream onto the surface of the separating wall thereby to avoid interference with the movement of air and fibers as a transient layer across the face of the separating wall. Instead, the air nozzles may be adapted to introduce the air stream as a substantially continuous blade extending across the housing, such as is described in the aforementioned copending application of Clark et al., of which this application is an improvement.

Positioned in closely spaced apart relation from the separating wall is a collecting wall 15 having foramen dimensioned to permit passage of air therethrough but to separate out the fibers on the surface thereof. The collecting wall may be a stationary member or it may be in the form of an endless belt moving in one direction and adapted continuously to separate fibers on the surface thereof to form an interfelted fibrous web. In any event it is desirable to locate the collecting wall in the fiber depositing zone over a suction device whereby air is withdrawn through the collecting wall to hold the deposited fibers on the surfaces thereof. In the event that the amount of air withdrawn through the collecting wall is greater than that which passes through the separating wall, the deficiency is made up by a slight inflow of air from the surrounding atmosphere into the space between the separating wall and the collecting wall thereby to permit the area to remain open to the atmosphere without interference with the movement of fibers and without dispersion of fibers out into the atmosphere as has been characteristic of fiber depositing systems heretofore employed when the area in the fiber depositing zone is allowed to remain open to the atmosphere.

To the present description has been made of a device of the type described and claimed in said copending application for causing air and fibers to move as a constant layer under positive pressure over the face of the separating wall to generate a type of shower-head principle whereby air and fibers in substantially uniform volumes and

concentration pass through the openings of the separating wall 13 to the collecting wall 15.

It has been found that considerable improvement in the transmission of fibers in uniform distribution and concentration through the separating wall results from the modification whereby the circulating movement of air and fibers about the housing is confined within a limited annular space adjacent the outer wall of the cylindrical housing 10. The linear movement of air and fibers is markedly increased thereby to secure better fiber distribution while at the same time improving the characteristics operating to maintain the shower-head principle for causing more uniform volumes of fiber and air to pass through the openings in the separating wall.

In accordance with the practice of this invention, characteristics of the type described for channeling the fiber entrained air streams is achieved by the use of a shell 16 of elliptical or cylindrical shape positioned within the housing to provide an annular space therebetween.

As illustrated in Figure 1, it is preferred to make use of an elliptical shell positioned to provide a decreasing spaced relation with the housing walls in the area adjacent the separating wall and an increasing spaced relation in the area therebeyond with maximum space adjacent the feed opening thereby to increase the turbulence and velocity of the air stream as it passes over the separating wall and materially to decrease the velocity of the air as it approaches and passes the feed opening thereby to provide for less interference with the feeding relation and less tendency for the fibers to be thrown outwardly by centrifugal force to form interfelted bundles which interfere with the uniform transmission of separated fibers through the separating wall. In Figures 2 and 3, illustration is made of the use of a cylindrical shell substantially concentrically mounted within the housing to define an annular space for circulation of the fiber entrained air stream.

With this modification in the construction, the air inlet nozzles 14 may be positioned to extend substantially tangentially into the annular space between the housing and shell either through the housing, as described and illustrated in Figures 1 and 2, or through the shell member as shown in Figure 3. When positioned in the outer cylindrical housing, it is best if the angular relationship of the introduced air stream is adjusted to direct the stream so as not abruptly to impinge upon the adjacent shell wall, otherwise the desired circulating movements will not result. It is preferred to avoid directing the air stream at any portion of the shell and to avoid directing the air stream so as to impinge on the separating wall portion where it might interfere with movement of air and fibers thereover.

When located to extend through the shell wall, it is only necessary to avoid directing the air stream onto the separating wall and to maintain an angular relation as nearly tangential as possible to achieve the desired turbulence coupled with circulating movement.

Various combinations of nozzles mounted on the cylindrical housing or shell wall may be arranged to give the desired air scrubber action embodying the described shower-head principle.

As shown in Figure 1, separated fibers are fed downwardly through the feed hopper 11, through the feed opening 12 into the interior of the cylindrical housing 10. One or more air streams at high velocity are introduced tangentially into the housing by air nozzles 14 located just beyond the fiber feed opening 12.

The air nozzles are positioned to direct the air stream tangentially into the housing to pass just below the shell but beyond the farthest end of the separating wall portion 13 located in the underside of the housing.

As a result of the introduction of such high velocity air streams tangentially into the housing, the air streams are caused conjointly but in somewhat turbulent movement to circulate about the housing within the space de-

fined between the shell and the inner wall of the housing. The fibers become uniformly entrained therein and are carried with the air stream about the housing so that the air and fibers move as a transient fluid layer over the inner face of the separating wall 13. As a result, the openings in the separating wall are kept substantially free of fibers and uniform volumes of fibers and air pass through the separating wall 13 to the collecting wall 15.

Air is withdrawn by exhaust means in communication with ductwork 17 from the underside of the collecting wall 15 in the fiber depositing zone to create a suction which anchors the deposited fibers onto the surface thereof.

By way of still further modification to achieve better fiber separation and distribution in the circulating air stream, breaker plates in the form of paddle members 18 are mounted to operate within the confined annular space 21 through which the air and fibers circulate. The breaker plates may be in the form of a rigid bar dimensioned to have a width substantially corresponding to the distance between the walls of the housing and the shell and a length corresponding to that of the housing so as substantially fully to occupy the space therebetween when positioned to extend radially between the shell and housing. The plate is adapted to be secured onto a shaft 19 rotatably mounted in the side wall 20 of the housing and having a portion extending therethrough for mounting a pulley or sheave adapted to be operatively connected to a driving means for imparting rotational movement. Bearing plates 22 and 23 are positioned on the shaft adjacent the inner and outer walls 20 of the housing so as to seal off the opening against the passage of air and fibers therethrough.

Rotational movement of the breaker plate or paddle wheel 18 in the clockwise direction in Figure 2 causes displacement of the fibers thrown toward the outer wall of the housing by centrifugal force to the inner portion of the space so as to effect better distribution. The plate also operates to minimize the agglomeration of fibers or the bunching of fibers during movement through the confining space and it further functions to impact the fibers and break up the fiber bundles or masses in a manner to secure separation and better fiber distribution.

Instead of a single paddle wheel of the type described, two or more aligned paddle wheels or plate members may be rotatively mounted on separate shafts for simultaneous rotational movement within the area between the housing and shell. For example, in Figures 3 and 4, there is illustrated an assembly formed with two paddle wheels 30 and 31 radially aligned and dimensioned to occupy the space between the shell and the housing. The plates may be dimensioned to correspond to one-half the distance between said cylindrical elements in the event that a meeting relation exists but, if the plates are adapted to be spaced so that one does not interfere with the rotational movement of the other, the plate members may be of larger dimension. Separate shafts 32 and 33 operatively connected to the breaker plates are provided with spindles 34 and 35 connected to driving means for rotational movement of the plates in the same or in opposite directions but with the outer plate preferably located in the clockwise direction to effect displacement of the fibers from the outer portions to which they are generally thrown by gravitational force.

The breaker plates or rotatable paddle wheels may be located in any portion of the housing other than between the air inlet nozzles and the separating wall and more than one breaker plate section may be used where desirable to achieve better fiber separation and distribution. It will be evident also that the breaker plates function to interrupt the linear flow of air and fibers and cause turbulent flow of a character which minimizes fiber agglomeration. While description has been given of a particular construction for the breaker plates, it will be apparent that the concepts of the invention embody the use of other con-

ventional disintegrating or separating apparatus capable of separating and/or displacing the fibers to achieve better fiber distribution as they circulate about the housing.

Other modifications, such as the use of a plurality of air inlets mounted both in the outer housing and in the shell wall or in one or the other may be used with or without radially extending air inlets to impart turbulence in addition to the breaker plates or separate therefrom in the absence of such breaker plates.

As used in the specification and in the claims, the term cylindrical as it refers to the shell and also to the housing is intended to include shells and housings of various shapes but of curvilinear contour such as ellipsoidal, oblate, and the like.

It will be understood that various changes may be made in the details of construction, arrangement and operation without departing from the spirit of the invention, especially as defined in the following claims.

I claim:

1. In apparatus for the air deposition of dry fibers to form a fibrous structure, a cylindrical housing having an inlet in one wall portion and a separating wall defining a wall portion spaced from the inlet and having openings dimensioned to permit passage of fibers, a shell substantially arranged within the housing to define an annular space therebetween, air nozzles extending into said annular space for directing high velocity streams of air in a tangential direction therein, and means for feeding fibers through the inlet into the space where the fibers become entrained in the air stream and are carried with the air as a moving layer across the face of the separating wall for passage therethrough in substantially uniform concentrations.

2. In apparatus for the air deposition of dry fibers to form a fibrous structure, a cylindrical housing having an inlet in one wall portion and a separating wall defining another wall portion having openings dimensioned to permit passage of fibers, a cylindrical shell arranged within the housing and offset in the direction of the separating wall to provide a smaller spaced relation therebetween and increasing spaced relation toward the inlet in the housing, air nozzles extending into the annular space for directing high velocity streams of air tangentially therein, and means for feeding fibers through the inlet into the annular space where the fibers become entrained in the air stream and are carried with the air as a transient layer across the face of the separating wall for passage therethrough in substantially uniform concentrations.

3. Apparatus as claimed in claim 1 in which the shell comprises an ellipsoidal member.

4. Apparatus as claimed in claim 1 in which the shell comprises an ellipsoidal member positioned to define a space of decreasing dimension between the shell wall and the separating wall portion of the housing.

5. Apparatus of the type claimed in claim 1 in which the air nozzles extend through the cylindrical housing into the annular space.

6. Apparatus of the type claimed in claim 1 in which the air nozzles are positioned in the cylindrical shell to direct the air streams tangentially into the annular space.

7. Apparatus of the type claimed in claim 1 in which the air nozzles are located both in the cylindrical housing and in the cylindrical shell for directing air streams tangentially into the annular space therebetween.

8. Apparatus for the air deposition of dry fibers to form a fibrous structure comprising a cylindrical housing having an inlet in one wall portion and a separating wall defining another having openings dimensioned to permit passage of fibers, a collecting wall spaced a short distance from the separating wall and having openings dimensioned to prevent passage of fibers, a cylindrical shell arranged within the housing to define an annular space therebetween, inlet means for directing high velocity streams of air tangentially into the space between the shell and housing, and means for feeding fibers through the

inlet into the annular space where the fibers become entrained in the air stream and are carried with the air about the annular space to pass as a moving layer across the face of the separating wall whereby fibers are carried with the air through the openings of the separating wall for separation onto the collecting wall.

9. Apparatus as claimed in claim 8 in which the collecting wall comprises an endless member moving in one direction to form a fibrous web thereon.

10. Apparatus as claimed in claim 8 which includes means for withdrawing larger volumes of air from the underside of the collecting wall than is able to pass through the separating wall whereby the deficiency is made up by a slight inflow of air from the surrounding atmosphere into the space between the separating wall and the collecting wall.

11. Apparatus for the air deposition of dry fibers to form a fibrous structure comprising a cylindrical housing having an inlet in one wall portion and a separating wall defining another having openings dimensioned to permit passage of fibers, a collecting wall spaced a short distance from the separating wall having openings dimensioned to prevent passage of fibers, a cylindrical shell positioned within the housing to define an annular space therebetween, air inlet means for directing high velocity streams of air tangentially into the cylindrical space, a paddle wheel assembly positioned within the annular space for rotational movement about an axis parallel to that of the housing, and means for feeding fibers through the inlet into the cylindrical space whereby the fibers become entrained in the air stream and are carried therewith about the cylindrical space for passage as a moving layer across a face of the separating wall whereby substantially uniform volumes of air and fiber pass through the openings thereof.

12. Apparatus for the air deposition of dry fibers to form a fibrous structure comprising a cylindrical housing having an inlet in one wall portion and a separating wall defining another having openings dimensioned to permit passage of fibers, a collecting wall spaced a short distance from the separating wall having openings dimensioned to prevent passage of fibers, a cylindrical shell positioned within the housing to define an annular space therebetween, inlet means for introducing high velocity streams of air tangentially into the cylindrical space, means for feeding fibers through the inlet into the cylindrical space whereby the fibers become entrained and are carried with the air stream about the cylindrical space for passage as a moving layer over the face of the separating wall whereby substantially uniform volumes of air and fibers are carried through the separating wall to the collecting wall, a paddle wheel assembly mounted in the annular space for rotational movement about an axis parallel to the axis of the housing and dimensioned lengthwise substantially to correspond to the length of the cylindrical space and dimensioned in width to correspond to the distance between the shell and housing, and means for rotating the paddle wheel assembly for effecting more uniform distribution and separation of fibers carried with the air about the cylindrical space.

13. Apparatus for the air deposition of dry fibers to form a fibrous structure comprising a cylindrical housing having an inlet in one wall portion and a separating wall defining another having openings dimensioned to permit passage of fibers, a collecting wall spaced a short distance from the separating wall having openings dimensioned to prevent passage of fibers, a cylindrical shell substantially concentrically positioned within the housing to define a cylindrical space therebetween, inlet means for introducing high velocity streams of air tangentially into the cylindrical space, means for feeding fibers through the inlet into the cylindrical space whereby the fibers become entrained and are carried with the air stream about the cylindrical space for passage as a moving layer over the face of the separating wall whereby substantially uniform

volumes of air and fiber are carried through the separating wall to the collecting wall, a paddle wheel assembly positioned within the cylindrical space for rotational movement about an axis parallel to the housing, and driving means for rotating the paddle wheels in a direction to displace the fibers from an area adjacent the housing wall to an area adjacent the shell wall during rotation of the fibers with the air stream about the cylindrical space.

14. Apparatus as claimed in claim 12 in which the paddle wheel assembly comprises a pair of breaker plates 10 mounted for rotational movement about separate radially

aligned axes parallel to the axis of the housing and dimensioned to have a width corresponding to one-half the distance between the walls of the housing and shell, and means for rotating the plates in opposite directions with the outer plate turning in a direction to displace the fibers inwardly from the portion adjacent the housing wall.
